UNITED STATES PATENT OFFICE.

FRANK LEWALD, OF CHICAGO, ILLINOIS.

DESIGN FOR A COLLAR-BUTTONER AND NAIL-CUTTER.

SPECIFICATION forming part of Design No. 31,349, dated August 8, 1899.

Application filed June 21, 1899. Serial No. 721,387. Term of patent 7 years.

To all whom it may concern:

Be it known that I, FRANK LEWALD, a citizen of the United States of America, and a resident of Chicago, Cook county, in the State of Illinois, have invented and produced a new and original Design for a Combined Collar-Buttoner and Nail-Cutter, of which the following is a specification.

Figure 1 is a front side elevation of a collar-buttoner and nail-cutter, showing my design. Fig. 2 is a plan or edge view of the same, and Fig. 3 is an end view enlarged.

My design for the collar-buttoner and nail-cutter consists in its entirety—that is, in the shape of the looped buttoner c, the handle b, the shank a uniting the handle and buttoner, and the peculiar spherical shaped termination f of the opposite shank portion a' of the handle forming the nail-cutter.

As shown in the drawings, the looped buttoner c is substantially oval-shaped, a portion of the shank is flattened to form the handle b, the intermediate part a uniting the handle b and buttoner c is round or cylindrical, terminating in the spherical end, from which latter the buttoner-loop directly extends. The opposite end portion a' of the said handle b is also cylindrical, its extreme end part f being substantially spherical. The latter has a circular opening d therethrough formed at right angles with the longitudinal axis of the handle and shank. The end member f is cut away at an angle or beveled to form a flat or plane surface, one edge of the latter intersecting said opening d and forming a V-shaped notch e.

What I claim is—

The design for a collar-buttoner and nail-cutter, substantially as herein shown and described.

Signed by me, at Providence, Rhode Island, this 15th day of June, A. D. 1899.

FRANK LEWALD.
